CLAIM

I claim the ornamental design for a brake for an in-line roller skate, as shown and described.

DESCRIPTION

FIG. 1 is a rear perspective view of the brake; FIG. 2 is a side elevational view of the brake shown attached to a typical skate, the skate being depicted in dotted lines; FIG. 3 is a rear elevational view of the brake; FIG. 4 is a front elevational view of the brake; FIG. 5 is a bottom plan view of the brake; and, FIG. 6 is a top plan view of the brake.

The broken line showing of a typical skate is for illustrative purposes only and forms no part of the claimed design.
